UNITED STATES PATENT OFFICE

ABRAM C. MOTT, JR., OF LANSDALE, PENNSYLVANIA, ASSIGNOR TO ABRAM COX COMPANY, OF LANSDALE, PENNSYLVANIA, A CORPORATION OF PENNSYLVANIA

BOILER FURNACE

Application filed March 4, 1927. Serial No. 172,894.

My invention relates to certain improvements in a sectional boiler having a tongue projecting over the fire-box of the boiler. In this type of boiler the products of combustion pass up between the tongue and through horizontal flues to the stack.

The object of my invention is to provide means for admitting air to mix with the products of combustion as they enter the space between the tongue, to increase combustion and to reduce the amount of smoke escaping to the flues.

In the accompanying drawings:

Fig. 1 is a sectional view on the line 1—1, Fig. 2, of a vertical boiler of the building-heating type and illustrating my invention;

Fig. 2 is a sectional view on the line 2—2, Fig. 1;

Fig. 3 is an end view of a portion of the boiler showing the end cover plates;

Fig. 4 is an enlarged sectional view of the air intake duct on the line 4—4, Fig. 6;

Fig. 5 is a sectional view on the line 5—5, Fig. 6; and

Fig. 6 is a side view partly in section of the air duct.

The sections 1 of the boiler are mounted upon a base 2 having bearings for the trunnions of a grate and enclosing the ash-pit.

The boiler sections 1 are made as shown in Figs. 1 and 2, each section having an overhead body portion 3 with channels in the sides forming flues 4 for the products of combustion, a back leg 5 forming the back of the fire-chamber 6 and tongues 7, which depend from the body portion and are located directly above the fire-chamber. The boiler just described is of a standard type.

In order to increase the efficiency of the boiler and to prevent, to a great extent, the escape of smoke from the boiler, air is admitted to the boiler. This air mixes with the products of combustion before the products enter the flues of the boiler.

In order to admit air at the proper point, the tongues 7 of the boiler sections are perforated at 8 (Figs. 1 and 2). The shape of the perforations is as shown in said figures.

A transversely arranged intake duct 9 is provided, the duct being made as shown in

Figs. 4, 5 and 6, and is so shaped as to rest in the perforations of the tongues of the boiler, as in Figs. 1 and 2.

The duct is made in three longitudinal sections 10, 11 and 12 in the present instance, and these sections are of a given length. Two or more lengths may be coupled together where the width of the boiler requires such arrangement.

The section 10 is the bottom section and is preferably shaped in cross-section as in Fig. 4, so as to rest firmly on the bottom of the perforations 8, the sides of said section 10 being arranged at an angle and terminating a short distance from the lower edge of the vertical side sections 11 and 12, forming a narrow passage for air to be drawn into the combustion chamber from the duct 9.

The two side sections 11 and 12 are preferably curved at their upper edges, and one section overlaps the other section as shown in Fig. 4 to form a substantial joint at this point. The two parts are held together by transverse bolts 13 (Figs. 5 and 6).

In order to secure the bottom section 10 to the side sections, the latter have projecting lugs 14 at intervals, and the bottom section also has lugs 15 aligning with the lugs 14, bolts 16 extend through slots in the lugs 14 and holes in the lugs 15. The lugs 15 of the bottom are so shaped as to properly separate the bottom section from the side sections, leaving slots 22 of proper width for air to pass from the duct to the combustion chamber of the boiler.

As stated above, the duct is made in a number of longitudinal parts depending upon the width of the boiler, the bottom section of one part abutting against that of the other part. One end of the side sections has a flange 17 which overlaps the end of the adjoining section, as shown in Fig. 6, the parts being held together by transverse bolts 18.

In order to close the opening in each of the side sections of the boiler between the duct 9 and the body of the section, a double cap-plate 19 is secured to each side section by screw-bolts 20, Fig. 3, and the two parts of the cap-plate are secured together by bolts 21 which pass through lugs on the parts.

I claim:—

1. The combination in a boiler furnace, of a base; a series of boiler sections arranged side by side, each section having a body portion extending over a combustion chamber and having a rear depending portion, said depending portions forming the back of the combustion chamber, each section having a flue directly in front of the rear depending portion and having transverse perforations in the walls of the overhanging portion communicating with an intermediate portion of the flue; and an air duct extending through the transverse perforations from side to side of the boiler, said air duct having a slot at each side to allow air to pass from the duct to the flue of the boiler furnace.
2. The combination in a boiler furnace, of a base; a series of boiler sections arranged side by side, each section having a body portion extending over a combustion chamber and having a rear depending portion, said depending portions forming the back of the combustion chamber, each section having a flue directly in front of the rear depending portion and having transverse perforations in the walls of the overhanging portion communicating with an intermediate portion of the flue and air duct located in said transverse perforations, said air duct consisting of a base section and two longitudinal side sections; and means for holding the sections in the assembled position, the base section being spaced from the lower edges of the side sections, to allow air to pass from the air duct to the combustion chamber of the furnace.
3. The combination in a boiler furnace, of a base; a series of boiler sections, including two side sections and a series of intermediate sections, said side sections forming the side of a combustion chamber, the intermediate sections having tongues extending over the combustion chamber, the several sections being shaped to form flues extending from the combustion chamber, the tongues having transverse perforations communicating with an intermediate portion of the flue; an air duct extending from one side of the boiler furnace to the other side and through the perforations in the tongues consisting of a base and two side sections, the base being spaced from the side sections to form narrow air passages; bolts securing the parts together, the duct being made of longitudinal sections secured together, said duct-sections extending through the side boiler sections; and cap plates surrounding the ends of the duct and closing the space not occupied by the duct.
